[57] CLAIM

The ornamental design for a boat boarding ramp, as shown and described.

DESCRIPTION

FIG. 1 is a top plan view of a boat boarding ramp showing my new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a left side elevational view thereof;

FIG. 7 is a perspective view thereof;

FIG. 8 is a top plan view of a second embodiment of the design shown in FIG. 1;

FIG. 9 is a front elevational view thereof;

FIG. 10 is a right side elevational view thereof;

FIG. 11 is a bottom plan view thereof;

FIG. 12 is a rear elevational view thereof;

FIG. 13 is a left side elevational view thereof; and,

FIG. 14 is a perspective view thereof.

FIG. 1

FIG. 2

FIG. 3

FIG. 4
